UNITED STATES PATENT OFFICE.

GEORGE J. MEYER, OF MILWAUKEE, WISCONSIN.

ADJUSTABLE RADIATION CONTROL FOR BALANCED-PRESSURE RADIATORS.

Application filed September 26, 1924. Serial No. 740,187.

This invention relates to means for controlling the heating effect of steam radiators of the balanced pressure type and comprises a swinging member having connection with the interior of the radiator and with the drain pipe and forming the overflow for the water of condensation within the radiator so that in its various angular adjustments it will cause said overflow to take place at different elevations and consequently determine the level of the condensation water remaining in the radiator so that the radiation area exposed to the action of the steam may be varied to suit the requirements.

With the above and other objects in view the invention consists in the adjustable radiation control for low pressure radiators as herein claimed and all equivalents.

Referring to the accompanying drawings, in which like characters of reference indicate the same parts in different views,

Fig. 1 is a front elevation of a radiator provided with an adjustable radiation controlling means in accordance with this invention, parts being broken away to show the water level;

Fig. 2 is a sectional plan view thereof, and

Fig. 3 is a sectional detail of the swivel connection with the overflow pipe.

In these drawings, 10 indicates the usual balanced pressure steam radiator receiving steam at its upper end through the steam pipe 11 and returning water of condensation through the return drain pipe 12. Instead of the drain pipe 12 having direct connection with the bottom of the radiator, the outlet pipe 13 conducting the water from the radiator terminates in a T-coupling 14, to which the drain pipe 12 connects, but direct communication between pipes 13 and 12 is prevented by the presence of a pair of overflow tubes 15 and 16, one contained 45 within the other and both fitting within the casing formed by the T-coupling 14 as will be now described.

The inner tube 15 has secured to its end a ring 17 forming a conical flange which fits 50 against a conical seat 18 provided for it around the opening into which drain pipe 12 is threaded. The outer tube 16 at its end fits around the ring 17 and within the cylindrical extension of the opening forming the 55 conical seat 18. Its edge is beveled forming a packing gland 19 between it and the

flange of ring 17 and the wall of the casing, which gland contains packing. A flange 20 around the tube 16 fits the bore of the casing 14, and a gland bushing 21 threaded in said bore of the casing holds packing 22 against said flange whereby it will be seen that the tubes are so mounted within the casing that they are capable of being turned in their seats. The outer tube 16 has openings 23 through which communication is had with 60 the interior of the radiator and both tubes are bent as shown, so that their outer ends swing in a plane at right angles to the axis of their pivotal seats permitting them to 65 travel close to the front or the rear of the radiator as the case may be. The inner tube terminates just short of the outer tube and a cap 24 is threaded on the latter.

Now it will be seen that, inasmuch as the 75 water of condensation cannot pass directly to the drain pipe 12, it rises in the outer tube 16 until it overflows the outer end of the inner tube 15, which forms an adjustable extension of the drain pipe, and the elevation 80 of this point of overflow determines the level of the water remaining in the radiator and consequently the area of the radiation surface above the water exposed to the action of the steam. By swinging the overflow 85 pipe to a vertical position the water level within the radiator will be caused to rise to its maximum with a consequent reduction in radiation area which may be such as to exclude the steam entirely. On the other 90 hand by swinging the overflow pipe to the horizontal position shown in dotted lines, the water level will be lowered to expose practically the entire radiating surface to the action of the steam. Any intermediate 95 adjustment of the overflow pipe will be accompanied by a corresponding change in the water level within the radiator so that the effective radiation surface may be varied to suit requirements. It is obvious that 100 other means may be employed for obtaining the swivel mounting of the adjustable overflow pipe so that the only entrance to the drain pipe is through the outer end of the inner tube, but the present construction is 105 particularly desirable for this purpose in view of the arrangement by which the tightening of the gland bushing 21 not only seals the outer tube 16 but, by forcing the inner tube 15 against its conical seat, seals it also.

The term "balanced pressure" as herein used is intended to apply to those heating

systems in which there is no substantially greater inlet pressure than outlet pressure to defeat the purposes of the invention.

What I claim as new and desire to secure 5 by Letters Patent is:

1. In a radiator, the combination with the outlet pipe and drain pipe, of an adjustable pivotally mounted overflow pipe comprising a pair of tubes, one within the other, 10 and one being in communication with the outlet pipe and the other in communication with the drain pipe.

2. In combination, a radiator having an outlet pipe, a T-coupling connected therewith, a drain pipe connected with the T-coupling, and an angular overflow pipe having swivel connection with the T-coupling and comprising a pair of tubes one within the other and one having communication 20 with the outlet pipe and the other having communication with the drain pipe.

3. In combination, a radiator having an

outlet pipe, a T-coupling connected thereto, a drain pipe connected to the T-coupling, an angular overflow pipe swiveled in the 25 T-coupling and comprising an inner tube having a conical flange on its end fitting on a conical seat of the drain pipe opening of the T-coupling, and an outer tube surrounding the inner tube with its end bearing on 30 said T flange and within the said opening of the T-coupling, a flange on said outer tube, a gland bushing fitting around the outer tube and threaded within the T-coupling and forming a packing gland with the flange 35 of the outer tube, said inner tube communicating with the drain pipe and said outer tube having openings communicating with the outlet pipe, and a cap threaded on the end of the outer tube.

In testimony whereof I affix my signature.

GEORGE J. MEYER.
